UNITED STATES PATENT OFFICE.

CLARENCE A. GUSTAVESON, OF WHITEWATER, WISCONSIN.

DESIGN FOR A TOY TRUCK.

60,986.

Specification for Design. Patented May 23, 1922.

Application filed October 8, 1920. Serial No. 415,710. Term of patent 3½ years.

To all whom it may concern:

Be it known that I, CLARENCE A. GUSTAVESON, a citizen of the United States, residing at Whitewater, in the county of Walworth and State of Wisconsin, have invented a new, original, and ornamental Design for a Toy Truck, of which the following is a specification, reference being had to the accompanying drawing, forming a part thereof.

Figure 1 is a side elevation of a toy truck showing my new design.

Figure 2 is a front end elevation of the same, and,

Figure 3 is a fragmentary plan view of the same.

I claim:—

The ornamental design for a toy truck, as shown.

CLARENCE A. GUSTAVESON.
